United States Patent Office

Des. 211,481
Patented June 18, 1968

211,481

TOY VEHICLE

David L. Seitzenger, Erie, and John R. Bonnett and John B. Quigley, Girard, Pa., assignors to Louis Marx & Co., Inc., New York, N.Y., a corporation of New York

Filed Apr. 20, 1967, Ser. No. 6,766

Term of patent 7 years

(Cl. D34—15)

FIG. 1

FIG. 2

FIG. 3

FIG. 4

FIG. 5

FIG. 6

FIG. 1 is a top plan view of a toy vehicle of our new design;

FIG. 2 is a side elevational view thereof;

FIG. 3 is a front view thereof;

FIG. 4 is a rear view thereof;

FIG. 5 is a rear view similar to FIG. 2 showing the opposite side thereof; and

FIG. 6 is a bottom plan view thereof.

We claim:

The ornamental design for a toy vehicle, as shown.
